UNITED STATES PATENT OFFICE.

CHARLES R. REID, OF SPRINGFIELD, OHIO, ASSIGNOR TO THE CAILLE BROS. CO., OF DETROIT, MICHIGAN, A CORPORATION OF MICHIGAN.

DESIGN FOR A CASING FOR COIN-ACTUATED MACHINES.

SPECIFICATION forming part of Design No. 37,040, dated July 12, 1904.

Application filed June 13, 1904. Serial No. 212,437. Term of patent 7 years.

To all whom it may concern:

Be it known that I, CHARLES R. REID, a citizen of the United States of America, residing at Springfield, in the county of Clark and State of Ohio, have invented a new, original, and ornamental Design for a Casing for Coin-Actuated Machines, of which the following is a specification, reference being had therein to the accompanying drawing, forming part thereof, in which—

The figure is a perspective view of a casing for coin-actuated machines of my new design.

What I claim as new, and desire to secure by Letters Patent, is—

The ornamental design for casing for coin-¹⁵ actuated machines as shown.

CHARLES R. REID.
